UNITED STATES PATENT OFFICE.

ANTONIO ARICO, OF PHILADELPHIA, PENNSYLVANIA.

SHUTTLE.

1,324,991.

Specification of Letters Patent. Patented Dec. 16, 1919.

Application filed March 26, 1919. Serial No. 285,235.

To all whom it may concern:

Be it known that I, ANTONIO ARICO, a subject of the King of Italy, residing at Philadelphia, in the county of Philadelphia and State of Pennsylvania, have invented 5 certain new and useful Improvements in Shuttles, of which the following is a specification.

One object of my invention is to provide 10 a shuttle for power looms and which will be so constructed as to provide an even tension on the thread as the shuttle passes across the race of the loom.

Another object is to so construct my improved shuttle that the thread from the bobbin therein can be quickly placed in a position to extend through the tension means and can be quickly released from the tension means:

20 A still further object is to firmly hold the bobbin within the shuttle and to provide means whereby the bobbin can be quickly inserted and removed.

These objects, and other advantageous 25 ends which will be described hereinafter, I attain in the following manner, reference being had to the accompanying drawings in which—

Figure 1 is a top plan view of my im- 30 proved shuttle,

Fig. 2 is an enlarged sectional longitudinal elevation taken centrally through my improved shuttle, the central portion being broken away,

35 Fig. 3 is a transverse section taken on the line 3—3 of Fig. 2,

Fig. 4 is a transverse section taken on the line 4—4 of Fig. 2,

Fig. 5 is a transverse section taken on the 40 line 5—5 of Fig. 2, and

Fig. 6 is an enlarged fragmentary plan view of a portion of my shuttle with certain of the elements removed.

Referring to the drawings, 6 represents 45 the elongated body portion of the shuttle having a central cavity 7 and a slot 8 in its bottom communicating with said cavity 7. The top 9 of the body portion 6 is provided with two lateral cavities 10 and 11 which 50 communicate at their inner ends with the central cavity 7. The central cavity 7 provides a space for a bobbin 12 having the yarn or thread 13 wound thereon in the usual manner.

55 A hole 14 extends through the side 15 of the body portion 6 into the cavity 10 and

provides an outlet passage for the yarn 13, as clearly shown in Fig. 1.

Two lugs 16 and 17 project from the side walls of the cavity 10 and are spaced apart 60 to provide a guideway 18 for the yarn 13 in passing from the bobbin 12 to the hole 14.

A threaded rod 19 extends through the body portion 6 and through a sleeve 20; 65 said sleeve being positioned on the bottom of the cavity 10. The rod 19 has a nut 21 screwed thereon at its bottom and positioned within a recess 22 in the bottom of the body portion 6. The upper end of the rod 19 is provided with an eyelet 23, said eyelet bearing 70 against the top of the sleeve 20.

A pivot pin 24 extends through the eyelet 23 and through two depending ears 25 on a plate 26. The ears 25 are positioned between the opposite ends of the plate 26, as 75 clearly shown in Fig. 2, and a coiled spring 27 is interposed between the bottom of the end portion 28 of the plate 26 and the bottom of the cavity 10. The spring 27 is operative to move the end portion 28 of the plate upwardly on the pivot pin 24 as an axis and thereby move the end portion 29 of said plate 26 downwardly.

A strip 30 of long pile fabric or the like 80 is secured to the end surface of the end portion 29 and has its fibers 31 extending downwardly and adapted to intermesh with fibers 32 of another strip 33 of pile fabric or the like which is secured to the bottom of the cavity 10. It will thus be seen that by pressing downwardly on the portion 28 of the plate 26 that the fibers 31 and 32 will be 85 separated and when thus separated the yarn 13 can be placed therebetween and the end drawn or threaded through the hole 14.

To facilitate this operation, the plate 26 has a notch 34 in its side so that the thread can be looped under the portion between the notch and the edge 35 of the end portion 29 of the plate 26. In passing back and forth 90 across the loom race, the shuttle will drag the yarn 13 through the hole 14 and between the fibers 31 and 32. Thus tension will be placed upon the yarn. The fibers 31 and 32 thus form fibrous jaws between which the 95 yarn 13 must travel before passing out of the hole 14.

In order to remove the plate 26, rod 19 and spring 27, it is merely necessary to remove the nut 21 when the entire structure 100 can be lifted out of the body portion 6. The top surfaces of the lugs 16 and 17 are

- positioned slightly below the top of the body portion 6 and form a stop to limit the downward movement of the portion 29 of the plate 26.
- 5 The bobbin 12 has a stem 36 which flares toward its free end. This stem 36 is adapted to be positioned within a socket provided by the recess 11 and rests upon a felt pad 37. A plate 38 has an end portion 39 which 10 is curved in cross section, as clearly shown in Fig. 5, and is adapted to embrace the upper portion of the stem 36. This end portion 39 follows the contour of the stem 36, as clearly shown in Fig. 2. The plate 38 is 15 pivotally connected by a pin 40 to the top of a rod 41; said rod being threaded at its lower end and provided with a nut 42, the nut being positioned within a recess 43 in the bottom of the body portion 6. The plate 20 38 has an opposite end portion 44 which overhangs the pivot pin 40 and a coiled spring 45 is positioned between the bottom of the end portion 44 and the bottom of the cavity 11. The spring 45 thus 25 tends to hold the end portion 39 in clamping contact with the stem 36 of the bobbin. Thus the bobbin is firmly held within the cavity 7 but may be quickly and easily removed or replaced by pressing 30 downwardly upon the end portion 44 of the plate 38.

While I have described my invention as taking a particular form, it will be understood that the various parts of my invention 35 may be changed without departing from the spirit thereof, and hence I do not limit myself to the precise construction set forth, but consider that I am at liberty to make such changes and alterations as fairly come 40 within the scope of the appended claims.

Having thus described my invention, what I claim as new and desire to secure by Letters Patent is:

1. A shuttle having a bobbin therein, said 45 bobbin having an outwardly flared stem, said shuttle having a recess providing a socket of the contour of said outwardly flared stem of the bobbin; and a plate having a portion for clamping said stem at a 50 position inwardly from the end whereby the bobbin is held against longitudinal movement; substantially as described.

2. A shuttle having a bobbin therein, said 55 bobbin having an outwardly flared stem, said shuttle having a recess providing a socket of the contour of said bobbin stem; a plate having a portion curved in cross section following the longitudinal contour of the flar-

ing stem; and means for holding said plate in clamping engagement with said stem 60 whereby the bobbin is retained against longitudinal movement; substantially as described.

3. A shuttle including a body portion; a rod detachably connected to said body portion; a plate pivotally connected to said rod; a pair of jaws respectively connected to said plate and body portion and between which the yarn must pass prior to passing out of the shuttle; and means for automatically moving said jaws toward each other; substantially as described.

4. A shuttle including a body portion; a rod detachably connected to said body portion; a plate pivotally connected to said rod; a pair of fibrous jaws respectively connected to said plate and body portion and between which the yarn must pass prior to passing out of the shuttle; means for automatically moving said jaws toward each other; and means providing a stop for limiting the extent of intermesh of the fibers of each jaw; substantially as described.

5. A shuttle including a body portion; a rod detachably connected to said body portion; a plate pivotally connected to said rod; a pair of jaws respectively connected to said plate and body portion and between which the yarn must pass prior to passing out of the shuttle; and means for automatically moving said jaws toward each other; said body portion having a hole in its side through which the yarn passes after passing between said jaws; said plate having a notch to facilitate the threading of said yarn 95 through said hole and the introduction of said yarn between said jaws; substantially as described.

6. A shuttle having a bobbin therein, said bobbin having a flaring stem; a plate having a portion curved in cross section and following the contour of said flaring stem; means providing a pivoted mounting for said plate; a spring operative upon said plate for moving said portion into clamping engagement with said stem; and means providing a resilient pad forming a seat for said stem oppositely disposed to said plate portion; substantially as described.

In testimony whereof I have signed my 110 name to this specification in the presence of two subscribing witnesses.

ANTONIO ARICO.
